Primary Examiner — Jennifer Rivard*Assistant Examiner* — Jennylou M Binas(74) *Attorney, Agent, or Firm* — David & Raymond Patent Firm; Raymond Y Chan(57) **CLAIM**

The ornamental design for a pool skimmer frame, as shown and as described.

DESCRIPTION

FIG. 1 is a top perspective view of a pool skimmer frame showing my new design;

FIG. 2 is a front view thereof;

FIG. 3 is a rear view thereof;

FIG. 4 is a left end view thereof;

FIG. 5 is a right end view thereof;

FIG. 6 is a top view thereof; and,

FIG. 7 is a bottom view thereof.

The broken lines depict portions of the pool skimmer frame that form no part of the claimed design.
